UNITED STATES PATENT OFFICE.

JOHN F. O'CONNOR, OF CHICAGO, ILLINOIS, ASSIGNOR TO WILLIAM H. MINER, OF CHAZY, NEW YORK.

COMBINED SPRING-GEAR AND DAMPENER.

1,288,661.

Specification of Letters Patent. Patented Dec. 24, 1918.

Application filed January 27, 1917. Serial No. 144,812.

To all whom it may concern:
Be it known that I, JOHN F. O'CONNOR, a citizen of the United States, residing at Chicago, in the county of Cook and State of Illinois, have invented a certain new and useful Improvement in Combined Spring-Gears and Dampeners, of which the following is a full, clear, concise, and exact description, reference being had to the accompanying drawings, forming a part of this specification.

This invention relates to improvements in combined spring gear and dampener.

The object of the invention is to provide an effective dampener for coöperation with a spring gear for railroad cars to overcome the undesirable shocks usually incident to the recoil of spring gears.

The invention further consists in improvements in the parts and devices and in the novel combinations of the parts and devices herein shown, described and claimed.

In the drawings forming a part of this specification Figure 1 is a vertical longitudinal section of a draft rigging showing my improvements in connection therewith. Fig. 2 is a horizontal sectional view of the structure illustrated in Fig. 1, and taken on the line 2—2 thereof. Figs. 3 and 4 are transverse vertical sectional views taken on the lines 3—3 and 4—4 respectively of Fig. 1. Fig. 5 is a perspective view of the wedge member employed with the dampener, and Fig. 6 is a perspective view of the combined friction blocks of the dampener and limiting stop for the gear proper.

In said drawings 10—10 denote channel shaped center or draft sills of a car underframe to which are secured a rear stop casting 11 and a front stop casting 12. The stop casting 11 is of substantially a rectangular form and has side walls 13—13 riveted to the sills, upper and lower horizontal walls 14—14 forming a guide way for the rear end of the yoke 15, and vertically extending flanges 16—16 forming the stop shoulders proper. The front stop casting 12 is also of rectangular or box-like form, and, as shown, comprises side walls 17—17, upper horizontal wall 18, lower horizontal wall 19 and 19^a, and vertical flanges 20—20, the latter forming the stops proper for the front follower of the gear. The portion 19 of the lower horizontal wall forms a table or support for the butt of the draw bar 21, and the portion

19^a is downwardly offset to provide sufficient clearance when the draw bar butt is inserted in position. The draw bar is connected to the yoke 15 by a key 22, which is extended through slots in the yoke arms and elongated slots in the side walls of the front stop casting and sills.

The spring gear proper, as shown, comprises a rear follower 23, a follower 24, and upper and lower twin springs 25—25, each preferably consisting of an inner and an outer coil. The gear is supported by a detachable saddle plate 26.

The dampener proper for the gear, as shown, comprises a front follower 27 which abuts the front stop casting, and a circular extension or thrust member 28 formed integrally with the follower 24 and which extends to the front follower 27 to thereby maintain said followers 24 and 27 at a fixed distance apart. The extension 28 is seated at its forward end on a lug 29 formed on the inner side of the follower 27 so as to maintain the parts in proper position. Co-operable with said extension or post 28 are two friction shoes or blocks 30—30, each having an inner cylindrical surface 31 frictionally engaging the post 28, and an outer wedge face 32 facing forwardly and with which cooperates a rectangular wedge member 33, (see Fig. 5). Said wedge member 33 encircles the friction blocks and has wedge faces 34—34 on the sides thereof cooperating with the opposite wedge faces of the friction blocks. The wedge member 33 is engaged by a relatively heavy spring 35 which bears at its front end against the follower 27. As clearly appears from Figs. 2 and 6, each of the wedge blocks 30 is provided with a rearwardly extending arm 36 recessed on its inner face as indicated at 36 to accommodate the intermediate follower 24 and permit the latter to move therein, and another recess 37 fitting over the rear follower 23. With the arrangement just described, it is apparent that the friction blocks 30 with their extensions are immovable with respect to the rear follower 23 but permit the necessary movement of the intermediate follower 24. Furthermore, the rearward extensions of the friction blocks, where the same are projected inwardly, as indicated at 38—38, form combined spring spacers and limiting stops to limit the travel of the gear and prevent overcompression of

the springs. The front follower 27 is supported by any suitable means, such as the tie-plate 39.

In assembling the gear and dampener, the 5 springs 25 are first placed between the followers 23 and 24, after which the friction blocks are applied laterally over the followers 23 and 24. Then the wedge member 33 is applied, then the spring 35 and finally 10 the front follower 27. With the parts thus assembled, it is apparent that the entire structure may be inserted vertically within the arms of the horizontal yoke, and all the parts there supported by the tie-plates 26 15 and 39.

In operation, upon inward movement of the draw bar, it is apparent that the friction blocks 30 are held stationary and consequently as the front follower 27 and intermediate follower 24 with its post 28 move inwardly, the friction between the blocks 30 and said posts will be gradually augmented due to the gradually increased pressure of the spring 35 against the wedge member 33. 25 The main springs of the gear 25 will be compressed in the usual manner and the parts limited in their movement by engagement of the follower 24 with the inward extensions 38 of the friction blocks. Upon release or recoil, it is apparent that movement of the parts will be retarded due to the frictional action which occurs between the posts 28 and friction blocks 30. In draft, the front follower 27 and intermediate follower 24 remain stationary while the rear follower 23 moves forwardly and at the same time forces the friction blocks 30 forwardly, thus obtaining similar action between the blocks 30 and the post 28.

40 From the preceding description, it will be seen that I have provided a spring gear of high capacity which is augmented by the frictional arrangement, the latter also serving effectively to dampen recoil. Furthermore, the parts are so arranged that they may be readily assembled and disassembled and the gear and dampener inserted into position without disturbing the yoke or draw bar.

50 I claim:

1. In mechanism of the character described, the combination with three followers, of stops for two of said followers, springs between a pair of said followers, a spring between one of said pair of followers and the third follower, and friction elements operatively connected with said first named pair of followers and acted upon by the last named spring to retard relative movement between the first named pair of followers.

2. In a draft rigging, the combination with a spring gear, of a spring dampener, the dampener and gear being simultaneously operable, and means operatively connecting 65 said gear and dampener and including an

extension from one follower of the spring gear forming an element of the spring dampener.

3. In a draft rigging, the combination with a spring gear, of a spring dampener 70 operable simultaneously with the gear, and means for operatively associating said gear and dampener, one element of the spring dampener having an extension disposed between the followers of the spring gear to act 75 as a limiting stop for the latter.

4. In a draft rigging, the combination with a spring dampener comprising a pair of followers having a fixed relation, blocks 80 frictionally engaging a portion of one of said followers, a wedge member co-acting with said blocks, and a spring coöperable with said wedge member, of a third follower, connections between said third follower and said blocks, and cushioning means between 85 the last named follower and one of the followers of the dampener.

5. In a draft rigging, the combination with a spring dampener comprising a pair of followers having a fixed relation, blocks 90 frictionally engaging a portion of one of said followers, a wedge member co-acting with said blocks, and a spring coöperable with said wedge member, of a third follower, connections between said third follower and 95 said blocks, cushioning means between the last named follower and one of the followers of the dampener, and extensions from the friction blocks disposed between the last named followers and adapted to limit relative approach thereof.

6. In a draft rigging, the combination with front and rear stop members, of end followers coöperable with said stop members, an intermediate follower having a post 105 extending therefrom to one of the end followers, friction blocks coöperable with said post, said blocks having wedge faces, a spring-controlled wedge member coöperable with said wedge blocks, cushioning means 110 located between said intermediate follower and the other end follower, and connections between the last mentioned follower and said blocks.

7. In a draft rigging, the combination 115 with a twin spring gear including a pair of followers, of a third follower, a thrust member extending from the last named follower to one of the followers of the gear, and means, including spring controlled friction 120 elements coöperable with said thrust member, for dampening the recoil of the spring gear.

8. In a draft rigging, the combination with front and rear stop members, of a front 125 follower, an intermediate follower, a rear follower, a thrust member extending between the intermediate follower and one of the end followers, friction blocks coöperable with said thrust member, said friction blocks 130

having a fixed relation with the other end follower, a wedge member coöperable with the friction blocks, a spring controlling said wedge member, and cushioning means between the intermediate follower and one of the end followers.

9. In a draft rigging, the combination with two end followers and an intermediate follower, of stops coöperable with the end followers, a post extending from the intermediate follower to the front end follower, friction blocks coöperable with said post, said friction blocks having arms extending rearwardly and recessed to accommodate the intermediate follower and the rear end follower, a spring controlled wedge member coöperable with said friction blocks, and cushioning means interposed between the intermediate follower and the rear end follower; a spring controlled wedge member coöperable with said friction blocks, and cushioning means interposed between the intermediate follower and the rear end follower.
10. In a draft rigging, the combination with two end followers and an intermediate follower, of stops coöperable with the end

followers, a post extending from the intermediate follower to the front end follower, friction blocks coöperable with said post, 25 said friction blocks having arms extending rearwardly and recessed to accommodate the intermediate follower and the rear end follower, a spring controlled wedge member coöperable with said friction blocks, and 30 cushioning means interposed between the intermediate follower and the rear end follower, said rearwardly extended arms of the friction blocks having inward extensions disposed between the intermediate and rear follower adapted to act as limiting stops to limit the relative approach of said followers.

In witness that I claim the foregoing I have hereunto subscribed my name this 24th day of Jan., 1917.

JOHN F. O'CONNOR.
